CLAIM

I claim the ornamental design for aerosol actuator for mousse product, as shown and described.

DESCRIPTION

FIG. 1 is a front and side perspective view of an aerosol actuator for mousse product showing my new design; FIG. 2 is a front elevational view of the aerosol actuator for mousse product of FIG. 1;

FIG. 3 is a rear elevational view of the aerosol actuator for mousse product of FIG. 1;

FIG. 4 is a side elevational view of the aerosol actuator for mousse product of FIG. 1, the opposite side view being a mirror image thereof;

FIG. 5 is a top plan view of the aerosol actuator for mousse product of FIG. 1; and,

FIG. 6 is an underside view of the aerosol actuator for mousse product of FIG. 1.
